F. A. RYTHER,

TRACTOR HITCH.

APPLICATION FILED JAN. 31, 1916.

1,275,761.

Patented Aug. 13, 1918.

Inventor:
Frank A. Ryther.
By *Charles E. Lord* Atty.

UNITED STATES PATENT OFFICE.

FRANK A. RYTHER, OF CHICAGO, ILLINOIS, ASSIGNOR TO INTERNATIONAL HARVESTER COMPANY OF NEW JERSEY, A CORPORATION OF NEW JERSEY.

TRACTOR-HITCH.

1,275,761.

Specification of Letters Patent. Patented Aug. 13, 1918.

Application filed January 31, 1916. Serial No. 75,202.

To all whom it may concern:

Be it known that I, FRANK A. RYTHER, a citizen of the United States, residing at Chicago, in the county of Cook and State of Illinois, have invented certain new and useful Improvements in Tractor-Hitches, of which the following is a full, clear, and exact specification.

My invention relates to tractor hitches.

It has among its objects to provide an improved hitch especially adapted to use in connection with headers and header binders whereby the same may be drawn in rear of a tractor. A further object of my invention is to provide such an improved hitch especially adapted to machines of standard construction wherein the point of draft is substantially the same as that in the horse pushed machine and wherein the draft connections enable the desired independent movement of the drawn machine and tractor and enable the same to make the turns readily without in any way interfering with any of the mechanism. A more specific object of my invention is to provide an improved hitch of simple construction which may be readily attached to or removed from the machines and which may be manufactured at small expense.

In the accompanying drawings I have illustrated one embodiment which my invention may assume in practice.

In these drawings:

Figure 1 is a plan view of a tractor and header binder equipped with my improvement, a portion of the tractor being omitted;

Fig. 2 is a sectional view taken on line 2-2 of Fig. 1 looking in the direction of the arrow, certain of the parts being broken to condense the illustration;

Fig. 3 is a detail transverse view substantially on line 3-3 of Fig. 2 looking in the direction of the arrow;

Fig. 4 is a sectional view taken on line 4-4 of Fig. 1 looking in the direction of the arrow.

In the form of my invention shown a header binder of standard construction is illustrated so that the same need not be specifically described save to say that it is mounted on an axle 1, which is in turn supported on a transport wheel 2 and main wheel 3, the binding mechanism 4 of the header and the heading mechanism 5, ad-

justable about the axle 1, being operatively connected to the main wheel in a well-known manner and driven therefrom. As in the standard header construction, a long rearwardly disposed pipe 6 is also connected to the axle 1, the latter being braced thereon by a suitable laterally extending brace 7. As usual, this pipe 6 is also provided with a tiller wheel 8, disposed beneath its rear end, controllable by a tiller 9, an operator's platform 10 being located above the rear end of the pipe so that an operator may ride thereon and control the several mechanisms of the machine through the usual mechanism (not shown). Disposed in front of the header binder is a tractor 11 which may be of any desired form.

In my improved construction a draft link 12 is pivotally connected to a bolt 13 at a point beneath the platform 10 and adjacent the rear end of the pipe 6. This link 12 extends forward and downward to a clamping bracket 14 carried on the stubblewardly disposed lower end of a transversely disposed, depending, supplemental frame member 15 which is attached at 16 to the pipe 6 and to a bracket 17 on the axle 1. As shown, the depending end of this member 15 which carries the bracket 14 is also braced on the axle 1 by an upward and laterally extending brace 18 attached to the bracket 17, and the bracket 14 is disposed longitudinally and on opposite sides of the depending portion of the member 15 and clamped thereto by a bolt 19. The forward end of the link 12 is pivotally connected to a bolt 20 carried at the rear end of this longitudinally extending bracket 14, and another link 21 is pivotally connected on a similar bolt 20 carried at the front end of the bracket, this link 21 extending forward and stubbleward to a point in front of the main wheel 3 and slightly at the grainward side thereof, where it is pivotally connected to the rear arm of a downturned U member 22 suspended by a chain 23 and an eye bolt 24 from the front cross frame member 25 of the header platform, the link being held in place by a holding plate 26 and suitable cotter pins 27. Connected to the opposite arm of this U member 22 is a third link 28, which extends forwardly and stubblewardly in the same straight line with the link 21, and which at its front end is suitably connected

in any desired manner; as, for instance, pivotally at 29, to the draw bar connections 30 on the tractor.

It will be noted that in my improved construction the draft of the tractor acts upon the header pipe 6 at a point beneath the platform 10; *i. e.*, at the same point as the draft of the horses normally used in pushing the machine. It will further be noted that 10 through my improved connections the link is disposed under the grain platform 5 and that it is so connected with the frame as to give ample clearance, all conflict between the link and the wheel, and also the link and 15 the standing grain, being effectually prevented by the provision of the swinging connection 23. Obviously, also, through the draft connection for the links 21 and 28, no strain is placed upon the front of the frame, 20 the entire draft being transmitted to the relatively rigid frame 15, 18, etc., and the pipe 6, as above mentioned. Other similar draft links may be employed for making a connection between the front part of one tongue, 25 push pole or steering element, to the front part of the tongue, push pole or steering element, of a following machine for connecting together any number of machines within reasonable limits. To this end, for the sake 30 of illustration, a suitable draft link 35 is provided, one end of which is suitably secured adjacent the rear end of the link 21, the link 35 extending rearwardly and grainwardly in a straight line with links 21 and 28. By 35 means of this straight line draft connection as above set forth, all side draft is eliminated.

In the operation of the device it will also be noted that there is great flexibility which enables the tractor to pass over uneven 40 ground, the header then being free to rise and fall independently thereof, and that when it is desired to make a turn, draft is exerted on the header at a point greatly facilitating the movement of the same relative to the tractor, the operator upon the platform 10 obviously being able to aid in steering the machine when necessary by suitable manipulation of the tiller 9. It should also be noted that in my improved 45 construction the links may be readily attached to, or removed from a standard header, the only additional parts required being the braces 15, 18, etc., and the chain connection 23. It is, of course, obvious that 50 instead of links of the length shown herein, the same may be made of any desired length and connected together although I find that with the parts as shown, the same may be formed into a very compact shipping package and very readily and cheaply manufactured.

While I have in this application specifically described one embodiment which my invention may assume in practice, it is, 60 of course, to be understood that the con-

struction may be modified and assume other forms without departing from its spirit, it being my intention to include all such constructions within the scope of the appended claims.

What I claim as new is:

1. In combination, a header having a platform and a rearwardly disposed steering element including a wheeled support for the rear end thereof, and means connected to 70 said steering element and disposed beneath said platform whereby the header may be drawn forward in the field.

2. In combination, a header having a platform and a rearwardly disposed steering element including a wheeled support for the rear end thereof, and a draft connection extending longitudinally of said element and beneath said platform whereby said header may be drawn forward in the field.

3. In combination, a header having a rearwardly disposed steering element and a grain platform, a draft connection extending longitudinally of said element and beneath said platform whereby said header may be drawn forward in the field, and means for limiting the movement of said draft connection.

4. In combination, a header having a rearwardly disposed steering element and a grain platform, a draft connection extending longitudinally of said element and diagonally beneath said platform whereby said header may be drawn forward in the field, and a depending swinging connection between the front end of said draft connection and said 95 grain platform.

5. In combination, a header having a rearwardly disposed steering element and a grain platform, a draft connection extending longitudinally of said element and diagonally beneath said platform whereby said header may be drawn forward in the field, and a depending swinging flexible connection between the draft connection and said grain platform.

6. In combination, an axle, a main wheel thereon, a steering element disposed rearwardly therefrom, a grain platform connected to said axle, a draft connection connected adjacent one end of said element extending longitudinally thereof and diagonally beneath said platform, and means for supporting said connection and preventing swinging of the same into engagement with said wheel or the standing grain.

7. In combination, a header axle, wheels thereon, a grain platform connected to said axle and disposed in front of said wheels, a steering element extending rearwardly from said axle, a wheeled support for the rear end of said element, and a draft connection disposed longitudinally of said element and beneath said platform.

8. In combination, a header axle, a grain platform connected to said axle, a rear-

- wardly disposed steering element connected to said axle, a manually controlled tiller wheel beneath the rear end of said element, and draft connections operatively connected at one end to said element at a point adjacent said tiller wheel disposed longitudinally of said element and diagonally beneath said platform.
9. In combination, a header axle, a grain platform connected thereto, a rearwardly disposed steering element connected to said axle, a manually controlled tiller wheel beneath the rear end of said element, a link connection including a plurality of links operatively connected to the rear end of said steering element and disposed longitudinally of said element and beneath said platform, and means mounted beneath said platform for limiting the movement of the front end of said link connection relative thereto.
10. In combination, a header axle, a grain platform connected thereto, a rearwardly disposed steering element connected to said axle, a manually controlled tiller wheel beneath the rear end of said element, a draft connection including a plurality of operatively connected links operatively connect-
- ed to said element and disposed longitudinally thereof and diagonally stubbleward beneath said platform, and a swinging connection for limiting the movement of the front end of said draft connection. 30
11. In combination, a header frame, a header axle member, a main wheel thereon, a rearwardly disposed steering element connected to said axle member, a frame member disposed transversely relative to said element and connected to said axle, said frame member having a depending portion, a draft connection operatively connected to 35 said steering element and disposed longitudinally thereof having one end operatively connected to the depending portion of said frame member, a coöperating draft member operatively connected to said depending portion and extending stubblewardly and forwardly across the path of said main wheel, and a swinging connection operatively connected to said header frame and the front end of said draft connection for limiting the 40 movement of the latter. 45

In testimony whereof I affix my signature.

FRANK A. RYTHE.
